UNITED STATES PATENT OFFICE.

SAMUEL B. SHELDON, OF BUFFALO, NEW YORK.

FUEL-FEEDING DEVICE FOR GAS-PRODUCING FURNACES.

No. 884,620.

Specification of Letters Patent.

Patented April 14, 1908.

Application filed July 25, 1907. Serial No. 385,530.

To all whom it may concern:

Be it known that I, SAMUEL B. SHELDON, a citizen of the United States, and a resident of Buffalo, in the county of Erie and State of New York, have invented certain new and useful Improvements in Fuel-Feeding Devices for Gas-Producing Furnaces; and I do hereby declare that the following is a full, clear, and exact description thereof, reference being had to the accompanying drawings, and to the letters of reference marked thereon, which form a part of this specification.

This invention relates to improvements in means for charging or feeding fuel to the fire chamber of a gas producing furnace and it consists in the matters hereinafter set forth, and more particularly pointed out in the appended claims.

My invention may be better understood by reference to the accompanying drawings in which,—

Figure 1 is a view showing, in central vertical section, the upper part of a gas producing furnace with my improved charging and feeding device mounted thereupon. Fig. 2 is a top plan view thereof showing parts broken away. Fig. 3 is an axial vertical section through the worm and worm-shaft constituting a part of my improved device. Fig. 4 is a detail axial vertical section through said shaft taken in a plane at right angles to the plane of Fig. 3. Fig. 5 is a view showing in central vertical section a modified form of my improved feeding and charging device. Fig. 6 is a view similar to Fig. 5 showing still another form of my improved device. Fig. 7 is a horizontal section, on the line 7—7 of Fig. 6.

As shown in said drawings (Figs. 1 to 4, inclusive), A indicates the fire chamber of a gas producing furnace, said furnace chamber being surrounded by a wall A¹ lined with fire brick A². Said fire chamber A is covered by a circular cover plate A³ which forms a support or bed plate for the fuel charging devices hereinafter to be described, and said plate is provided with a central circular opening a through which fuel is fed to the fire chamber. The fuel feeding and charging devices comprise a receptacle or hopper B mounted above the circular plate A³ on posts or pillars B¹ and joined at its bottom to the upper edge of a cylindric casing or tube B² which extends through the opening a. Said hopper B is provided on its outer periphery with a circular ring or rim b, comprising a

vertical member b¹ which is fixed to the wall of the hopper, and a horizontal member b² which rests upon the pillars B¹. At points above the pillars B¹ said ring is provided with radially extending vertical stiffening flanges b³. In said tube B² is arranged a vertical rotative shaft C provided with an outwardly directed spiral flange in the form of a screw or worm C¹, of moderate pitch, which rotates within the cylindric casing B² and, by its rotation, effects the downward feed of the fuel through said casing into the fire chamber A. The said worm is extended at its lower end and widened to form an inclined deflector or chute C² which, by its rotation, scatters or distributes the fuel in the fire chamber. In order to prevent the escape of gas through the opening a, a water seal is provided between the casing and the cover plate A³. The sealing device illustrated comprises an annular trough formed on the upper surface of the cover plate A³ by a vertical flange a¹ rising from said plate around the outer periphery thereof, and a like flange a² extending around the margin of the opening a. A circular flange or plate b⁴, fixed to the outer surface of the casing B², is provided at its outer edge with a downwardly directed vertical flange b⁵ which extends into the said trough and below the level of the water in said trough. In the upper part of said hopper B is a circular opening in which is fitted the neck e of a smaller hopper E by means of which fuel is fed to said hopper B. Said neck e is normally closed at its lower end by means of a valve or bell e¹ fixed to the lower end of a vertical shaft e² by means of which it may be raised or lowered.

The rotative shaft C extends upwardly through the hopper B and is supported in the casing B² by being secured at its upper end centrally to a circular, horizontal rotative bearing member C², which rests upon bearing balls d arranged in an annular ball race which constitutes part of a stationary or non-rotative lower bearing member D located in a central opening in the top of the hopper B. Said bearing member D is supported at the top of the hopper by means of braces B³ which extend diagonally from points beneath said bearing member to points in the interior of the hopper adjacent to the upper ends of the posts B¹, at which points they are secured to the wall of the hopper. The joint between the rotative parts at the top of the hopper B and the top of the hopper is sealed by means

2

of a downwardly directed flange c^1 at the outer edge of the bearing member C^3 which dips below the level of water in an annular trough which extends around the marginal part of the bearing member D . The bearing member C^3 is provided around its periphery with gear teeth c^2 by means of which it may be rotated to rotate the worm C^1 and feed the fuel through the casing B^2 as above described. Said bearing member C^3 is likewise provided on its upper surface with an upwardly facing ball race c^3 between which and a downwardly facing ball race d^1 on a stationary annular member D^1 are arranged bearing balls c^4 . Said stationary member D^1 is supported by curved stationary supporting members d^2 which are fixed to the non-rotative bearing member D . The purpose of the last described ball bearing formed between the rotative member C^3 and the stationary member D^1 is to prevent the shaft C from rising and from being thrown out of line by the thrust of a driving pinion upon the gear teeth c^2 , as might occur if said shaft were provided with only one bearing.

Means are provided as follows for cooling the rotative shaft and worm and the casing B^2 . As shown in the sectional views Figs. 3 and 4, the shaft and the worm are hollow or tubular and the hollow interior of the worm is in communication throughout its entire length with the hollow interior of the shaft. C^5 indicates a pipe arranged in the tubular shaft and provided at its lower end with branches C^6 and C^7 leading to the upper and lower parts, respectively, of the chute C^2 . By means of said pipe water is conveyed to the lower end of the worm and thence circulated upward through the tubular shaft and the tubular worm and is discharged through an overflow pipe c^8 at the upper end of said shaft. The casing B^2 comprises double walls forming between them an annular water jacket to which water is conveyed by a pipe b^6 . The water is discharged at the upper part of said jacket through an overflow pipe b^7 . The outwardly extending horizontal flange b^4 on the outer surface of said casing is cooled by water in a trough formed on the upper surface of said horizontal flange, by means of an upward extension of the vertical flange b^5 around the outer margin thereof. The said trough is supplied with water from the overflow pipe b^7 .

While the cylindric casing B^2 , surrounding the worm shaft, is stationary or non-rotative and the cover plate A^3 of the fire chamber is fixed or stationary, the opening a in said plate is made larger in diameter than the lower end of the said casing B^2 , which projects through the said opening, so that the said casing B^2 is entirely out of contact with the said cover plate; this construction being employed to prevent the communication of heat to the said casing from the said cover

plate, which is exposed to the heat of the burning fuel in the fire chamber. The joint between said cylinder and the cover plate is sealed to prevent the escape of gas by the annular flange b^4 and vertical flange b^5 , which latter dips into the water contained in the sealing trough formed in the cover plate, as hereinbefore described. The entire cover plate is cooled by the water in the trough formed on said top plate by the upright flanges a^1 a^2 at its inner and outer margins. 70 75

The escape of gas from the top of the hopper B is prevented by the water seal between the margins of the bearing plate C^3 and the fixed bearing ring D , while the escape of gas from said hopper through the smaller hopper E is prevented by the valve or bell e^1 by which the outlet at the lower end of said hopper E is kept normally closed. 80

In the operation of the apparatus constructed as hereinbefore described, fuel is fed from the smaller hopper E to the large hopper B by opening the valve or bell e^1 which latter is closed after the introduction of each charge of fuel. The worm shaft C 90 and worm being maintained continuously in rotation, the fuel is fed from the hopper B downward through the casing B^2 into the fire chamber. The said worm C extends at its upper end far enough up into the hopper 95

B to act upon the coal in the lower part of the hopper and to push or carry the same downwardly through the said casing B^2 , as the worm revolves; it being understood that inasmuch as the said casing B^2 is stationary, 100 the worm acts to feed the fuel downwardly therefrom in the manner of a spiral conveyer, although in this instance the downward movement of the coal is aided by the action of gravity. The rate of feed of the coal, 105

however, is determined or controlled by the speed of rotation of the worm. Upon reaching the lower end of the worm the coal slides downwardly over the deflector or chute C^2 ; the latter in its rotation spreading 110 or scattering the coal evenly in an annular path; the coal so delivered to the fire chamber being spread over the entire surface of the fire, or less than the entire surface as desired, in accordance with the angle at 115 which the chute is arranged. It is evident that by rotating the shaft and worm at a suitable speed the fuel can be fed to the fire chamber at any desired rate of feed and that the worm acts to control and render uniform the downward movement of the coal through the casing B^2 . By stopping the rotation of the worm, the feeding of the coal is stopped; for the worm is of such pitch 120

that the fuel will be prevented by friction from sliding down the inclined upper surface thereof, through the action of gravity, when the worm is not in rotation. When the worm is rotated, however, the coal by its frictional contact with the casing remains 125 130

practically non - rotative and slips down through the tube between the convolutions of the rotating worm.

In Fig. 5 is shown a modified form of construction in a feeding device embracing the general features hereinbefore set forth. In this instance the general construction of the producer, including that of the cover plate A³, the hopper B, the smaller hopper E and the supporting means for said hoppers is generally the same as before described. In this instance, however, the hopper E is shown as located centrally over the hopper B; and the rotative shaft C of the device hereinbefore described is replaced by a stationary upright shaft F and the casing B² thereof by a rotative casing or upright cylinder G provided on its inner cylindric surface with an inwardly directed spiral flange, forming an internal screw or worm G¹. At its lower end said worm is extended into the fire chamber in the form of an inclined deflector or a chute G² which by its rotation acts to scatter the fuel over the surface of the fire bed. At its upper end said cylinder G meets the open lower end B of the stationary hopper B and at its lower end extends into the circular opening a in the cover plate A³ of the fire chamber. The shaft F is rigidly supported at its upper end by attachment to a hub f which is supported by radial arms F¹ attached at their outer ends to the wall of the hopper B at points adjacent to the upper ends of the posts B¹. At its lower end said shaft engages, and is held from lateral movement, by a transverse bar f¹ attached at its ends to the rotative casing G at the bottom of the latter and provided with a bearing aperture into which the cylindric lower end of said shaft F extends. Said shaft F is provided with radially extending longitudinal flanges or ribs F², of which two are illustrated in the drawing. Said flanges or ribs F² extend upwardly into the hopper B and by their engagement with the coal in the lower part of the hopper and in the interior of the cylindric casing G, prevent the coal from rotating with the casing and worm. The said casing G is shown as supported upon the cover plate A³ in such manner as to permit the free rotation of said casing. In the particular construction shown, an annular, upwardly facing bearing or ball-race a³ is formed on the top surface of the plate A³, around the central opening a and exterior to the upwardly extending flange a² thereon, while the said casing G is provided near its lower end with an outwardly extending flange g on the outer margin of which is formed a vertical depending flange or ring g¹, which extends downwardly from the flange g outside of the said flange a² on the cover plate. Said ring g¹ is provided on its lower margin with an annular downwardly facing bearing or ball-race; between which

and the upwardly facing annular bearing a³ are located a plurality of bearing balls g². Said bearing balls carry the weight of the cylinder g and enable the same to be easily turned or rotated. Any suitable means will be provided for giving rotative movement to the said casing G, said means being shown in the drawings as comprising beveled gear teeth g³ formed on the top of the ring g¹ and a beveled driving pinion g⁴ intermeshing with said gear teeth. The joint between the casing G and the cover plate A³ is sealed by a water seal, formed by the water trough on the upper surface of the cover plate and the ring g¹ on said casing, which extends downwardly into the water in said trough. The joint between the upper end of the casing G and the bottom of the hopper B is sealed by an annular trough, adjacent to the upper margin of said cylinder, formed by means of an outwardly and upwardly extending flange g⁶ thereon into which depends the lower edge of a vertical, annular flange b⁸, attached to and extending downwardly from the outer surface of the said hopper B. Means are provided for water cooling the parts exposed to the heat of the fire, as follows: The shaft F and the vertical ribs F² F² thereon are made hollow or tubular; the hollow interiors of the ribs being in connection with the interior of the shaft throughout the length of said ribs. Water is supplied to the lower end of said shaft by a supply pipe f³ which passes downwardly through the center thereof, and overflow water is conducted from the shaft by a pipe f² leading from the upper end thereof. The cylinder G has double walls forming between them an annular water space, while the worm G¹ is hollow and is connected throughout its entire length with the said water space. For supplying water to the interior of the casing and hollow worm, suitable supply and return pipes will be connected with the cylindric casing by means adapted to permit rotation of the latter. Such water pipe may be arranged in any well known or preferred manner and it is not deemed necessary to illustrate the same in the drawings. The cover plate A³ is kept cool by the water in the sealing trough in its upper surface, which also keeps cool the bearing between the ring g¹ and said plate.

The operation of the device shown in Fig. 5 is generally similar to that of the device shown in Figs. 1 to 4 inclusive, coal being fed to the hopper B from the smaller hopper E and being fed downwardly through the casing G, by the action of the worm G¹ therein, during the rotation of the casing. The turning of the mass of coal within the said casing is prevented by the wings or ribs F² on the stationary shaft F. The coal passing from the lower end of the worm slides downwardly over the inclined chute or de-

5 reflector G^2 , which forms a downward extension of the lower end of said worm and is, by the action of said chute or deflector, distributed or scattered uniformly over the surface of the fire bed.

10 The modified form of construction shown in Figs. 6 and 7 comprises a fire chamber provided with a top plate A^3 , a fixed or stationary fuel hopper B and a smaller feed hopper E , arranged as shown in Figs. 1 to 4. In this instance the hopper B communicates at its lower end with the interior of an upright cylindric casing I within which is arranged a vertical, rotative shaft J . The 15 cylindric casing I is fixed or stationary, being secured to and supported by the hopper B , and its open lower end registers with the central opening a in the cover plate A^3 . In order to prevent communication of heat 20 from the cover plate to the casing said lower end of the casing is free from contact with the cover plate. A water seal is formed between the lower end of the casing and the cover plate, consisting of a downward extension i of the casing, larger in diameter 25 than the main part thereof, which surrounds the annular flange a^2 on the cover plate. Water placed in the trough formed by the cover plate and the flanges a^1 a^2 thereon, 30 constitutes a water seal between the cover plate and the said casing I . The stationary cylindric casing I is provided with an inwardly extending spiral flange, forming an internal screw or worm I^1 . The shaft J is 35 provided with radially and longitudinally extending flanges or ribs J^1 J^1 , of which two are shown in the drawing as extending from opposite sides of said shaft. Said flanges or ribs extend upwardly into the lower part of 40 the hopper B and in the rotation of the shaft serve to impart rotation to the mass of fuel in the lower part of the hopper and in the said casing, with the result that the coal 45 is carried downwardly through the casing between the convolutions of the worm. To the lower end of said shaft J is fixed an inclined chute or deflector J^2 , which rotates with the shaft and operates in the same manner as the inclined chutes or deflectors 50 hereinbefore described to distribute the fuel, which is delivered to its upper end, uniformly over the surface of the fire bed. The supporting means for the shaft J , illustrated in said Fig. 6, are like those illustrated in 55 Figs. 1 to 4 for supporting the shaft C therein shown, and are correspondingly lettered in the drawings. For water cooling the parts of the device which are most exposed to the heat of the fire, the following 60 construction is illustrated in Fig. 6. The shaft J and the vertical ribs J^1 J^1 thereon are made hollow or tubular and are in connection with each other throughout the entire length of the ribs. Likewise, the chute or 65 deflector J^2 is made hollow and has its hol-

70 low interior in connection with the interior of the shaft. Water is supplied to the shaft and chute or deflector by means of a pipe j which passes downwardly through the center of the shaft and is branched at its lower end; 75 the branches leading respectively to the upper and lower ends of said chute J^2 substantially in the manner hereinbefore described in connection with the chute C^2 and illustrated in Fig. 4. The waste water is 80 led away through an overflow pipe j^1 at the upper end of the hollow shaft J . The cylindric casing I in this instance is formed with double walls and the worm I^1 is hollow and in connection throughout its length with the 85 annular water space formed between the double walls of the casing. Any suitable means will be provided for supplying water to and conducting it away from the interior of the hollow casing and worm. In this 90 instance, as in the forms of apparatus previously described, the cover plate over the fire chamber will be kept cool by water in the sealing trough on its upper surface.

I claim as my invention:

1. The combination with a fire chamber provided with a metal cover plate having an opening through which fuel is fed to said chamber, of a fuel hopper closed at its top by a top wall, means for introducing fuel into 95 said fuel hopper without opening the same to permit the escape of gas therefrom, fuel feeding mechanism, comprising two members, one of which consists of an upright cylindric casing and the other of an upright shaft 100 within said casing, one of said members having rotative movement relatively to the other and one of said members being provided with a spiral rib or worm, a water seal between the rotative member and the fuel 105 hopper and a water seal between the said casing and the cover plate.

2. The combination with a fire chamber, provided with a metal cover plate, said cover plate having a central opening through which the fuel is fed to said chamber, of a fuel hopper closed at its top by a top wall, means for introducing fuel into the fuel hopper without permitting the escape of gas therefrom, fuel feeding means comprising two members, to-wit, an upright cylindric casing and an upright rotative shaft within said casing, one of 115 said members being provided with a spiral flange or worm, a water seal between the lower end of said casing and the cover plate 120 and a water seal between the rotative shaft and the said hopper.

3. The combination with a fire chamber, of a fuel hopper closed at its top by a top wall, means for introducing fuel into the said fuel hopper without permitting the escape of gas therefrom, fuel feeding means comprising two members, to-wit, an upright cylindric casing communicating at its upper end with 125 said hopper, and an upright rotative shaft 130

located in said casing and extending at its upper end through the said top wall of the fuel hopper, one of said members being provided with a spiral flange or worm, a water seal between the shaft and said top wall of the fuel hopper, and a water seal between the said casing and cover plate.

4. The combination with a fire chamber, of a fuel hopper closed at its top by a top wall, means for introducing fuel into the fuel hopper while maintaining the same closed to prevent escape of gas, feeding mechanism comprising two members, to wit, an upright cylindric casing communicating at its upper 15 end with the bottom of the hopper, and a rotative shaft located in the casing and extending through the top wall of the hopper, one of said members being provided with a spiral flange or worm, a fixed bearing ring 20 surrounding the upper end of the shaft, and connected with said top wall of the hopper, a horizontal bearing plate attached to the upper end of the shaft and having bearing engagement with said ring, a water seal between said bearing plate and ring, and a water seal between the said casing and cover plate.

5. The combination with a fire chamber provided with a metal cover plate, said cover 30 plate having an opening through which the fuel is fed to said chamber, of a fuel hopper closed at its top by a top wall, fuel feeding means comprising two members, to-wit, an upright cylindric casing communicating at 35 its upper end with the said hopper and an upright shaft extending through said casing, one of said members having rotative/movement with respect to the other and one of said members being provided with a spiral flange 40 or worm, a feed hopper having an opening in its bottom which extends through the top wall of the fuel hopper, a valve closing the bottom of said feed hopper, a water seal between the rotative member and the hopper, 45 and a water seal between the lower end of said casing and the cover plate.

6. The combination with a fire chamber, of fuel feeding mechanism comprising two members, to-wit: an upright cylinder casing, 50 and an upright shaft within said casing, one of said members having rotative movement relatively to the other and one of said members being provided with a spiral flange or worm, the member to which the said flange 55 or worm is attached and the worm being hollow and in communication with each other

to provide for the circulation therein of a cooling liquid.

7. The combination with a fire chamber, of a fuel hopper provided with a top wall, feeding mechanism comprising two members, to wit, an upright cylindric casing connected at its upper end with the bottom of the hopper, and a rotative shaft extending through the hopper and casing, one of said members being rotative relatively to the other and one of said members being provided with a spiral flange or worm, a lower fixed bearing ring in the upper part of said hopper, which is connected with the top wall thereof, radial arms 60 supporting said bearing ring from the side walls of the hopper, a bearing plate affixed to the upper end of said shaft, an upper fixed annular bearing ring, located above said bearing plate, and arms or brackets rigidly 65 supporting said last named bearing ring from the lower bearing ring.

8. The combination with a fire chamber, of a fuel hopper provided with a top wall, feeding mechanism comprising two members, to 70 wit, an upright cylindric casing, communicating at its upper end with the hopper and a rotative shaft extending through the hopper and casing, one of said members being rotative relatively to the other and one of said 75 members being provided with a spiral flange or worm, a fixed bearing ring in the upper part of the hopper which is connected with the top wall thereof, a bearing plate affixed to the upper end of the shaft and bearing on 80 the said fixed bearing ring, and a water seal between the upper end of said shaft and the top of the casing, formed by a groove in the said ring, and a vertical flange on the bearing plate extending downwardly into said groove. 85

9. The combination with a fire chamber, of a fuel hopper and feeding means comprising an upright cylindric casing and an upright rotative shaft located within said casing, said shaft being provided with a worm, said shaft 90 and worm being hollow, and the worm having its interior space in communication with the interior of the shaft, and water supply and return pipes connected with said shaft.

In testimony, that I claim the foregoing as 105 my invention I affix my signature in the presence of two witnesses, this 20th day of July A. D. 1907.

SAMUEL B. SHELDON.

Witnesses:

A. C. BYAM,
A. H. VOGEL.
